UNITED STATES PATENT OFFICE.

WILLIS W. CASE, JR., OF DENVER, COLORADO.

OIL-FORGE FOR DRILL-STEEL.

1,077,803.

Specification of Letters Patent.

Patented Nov. 4, 1913.

Application filed May 1, 1913. Serial No. 764,911.

To all whom it may concern:

Be it known that I, WILLIS W. CASE, Jr., a citizen of the United States, residing in the city and county of Denver and State 5 of Colorado, have invented certain new and useful Improvements in Oil-Forges for Drill-Steel; and I do hereby declare the following to be a full, clear, and exact description of the invention, such as will enable 10 others skilled in the art to which it appertains to make and use the same.

This invention relates to improvements in forges, and more particularly to an improved oil forge for drill steel.

15 When the old coal or coke forges, the coal or coke invariably contains considerable sulfur, causing the drill steel to become sulfurized, whereby the steel tends to chip very easily, rendering the same ineffective 20 after short usage. Another principal objection to oil forges heretofore constructed is the noise and smoke created, and one of the objects of the present invention is to provide a forge which has all of the advantages 25 of an oil forge over a coal or coke forge, and, at the same time, eliminates the objectionable features of noise and smoke.

With this and other objects in view, the 30 invention consists of the novel features of construction and in the combination and arrangement of parts, as will be more fully described in the following specification and pointed out more particularly in the appended claims.

35 While the invention is not restricted to the exact details shown and described, still, for the purpose of more clearly understanding the same, reference is had to the accompanying drawings, illustrating a practical 40 embodiment of the invention, in which drawings like characters designate the same parts in the several views, and in which:

Figure 1 is a central sectional plan view through the combustion chamber of the 45 forge, taken on a plane along the line 1—1 of Fig. 2, the burner and outside connections therefor being shown in plan; Fig. 2 is a view in elevation, looking toward the rear of the forge; Fig. 3 is a central vertical 50 sectional view, taken on a plane transversely of the forge; and Fig. 4 is a view in end elevation.

The forge proper may be supported in any suitable way, but, in the drawings, this 55 has been illustrated by a pair of semi-cylindrical metal supports 1 in the form of hol-

low base plates, forming a space 2 therebetween for substantially housing the fan and motor hereinafter referred to. These base members are suitably flanged at their 60 bottom and side edges, indicated at 3, and at their upper edge 4. These base members are spaced apart, as shown, and on top of same is mounted an iron sectional casing 5 and 6, forming the rear and front sheathing or jacket for the lining of the combustion chamber of the forge. The front and rear casing members 5 and 6 are also provided with the inwardly-disposed bottom sections 7 (Fig. 3), forming a support for 70 the lining of the combustion chamber, and they are also provided with upper and lower external flanges 8 and 9, the former being adapted to seat on the flanges 4 of the base supports and secured thereto by means of 75 bolts 10. This sectional casing 5—6 is of oval shape, as seen more clearly in Fig. 1, and contains a fire pot formed of the best fire clay, which is preferably molded in two longitudinal sections having its exterior 80 side wall of oval contour, adapted to be snugly jacketed by the casing 5—6.

The interior wall of the fire pot or combustion chamber is of peculiar conformation. The bottom 11 is bowl-shaped, the 85 vertical wall curving upwardly, as shown more clearly in Fig. 3. The front and rear sections 12 and 13, of the fire pot are provided centrally on their inner surfaces with opposed projections, which are of pyramidal 90 form, the projection 14 on the front plate being intact, while the projection 15 on the rear plate is truncated, and the rear wall 13 is provided with a bore 16, passing through the truncated projection 15 and adapted to 95 receive the nozzle 17 of the oil burner 18. The pyramidal projection 14, being directly opposite and in alinement with the burner opening 16, acts as a deflecting wall or baffle against which the flame impinges, diverting 100 the same in a swirling fashion around the combustion chamber, as will be hereinafter more fully referred to. As before stated, the combustion chamber of the fire pot is preferably built up of the best fire clay in 105 two longitudinal sections, but these do not extend to the top of the casing 5—6, but only to a position substantially above the pyramidal projections or baffles 14 and 15. Mounted on top of these sections 12 and 13 110 are located sectional top members 19 of fire clay, which members are of oval contour

exteriorly, registering with the outer surface of the sections 12 and 13, and the interior faces of these top members 19 are curved upwardly and inwardly forming a 5 continuation of the upper curved surfaces 14^a and 15^a of the pyramidal projections, the lower faces of these pyramidal projections also being of curved contour, merging into the lower or bowl-shaped surface of the bottom of the fire pot. It will be seen that the 10 curvature of the upper members 19 forms an overhanging ledge or shoulder 21 extending like a rim around the top of the fire pot, tending to deflect and swirl the 15 flames and products of combustion inwardly and downwardly, as will be more fully referred to.

22 designates the walls of the fire clay cover formed in sections and connected by a 20 beveled key block 24 of fire clay extending transversely above the fire pot, as indicated by dotted lines in Fig. 2, the cover being also provided with a lateral passage above the fire pot and below the key block 24, extending transversely across the forge and having a rear opening 25 and a front opening 26, providing means for inserting the work within the forge in contact with the flames, and which openings allow the work 30 to be under observance at all times, an advantage over coal or coke forges, where the operative is obliged to work in the blind, sometimes causing considerable loss of steel by burning. The cover walls 22 are also 35 provided with an iron jacket or casing, formed of two longitudinal sections 27, having vertical top flanges 28, vertical end flanges 29, and horizontal base flanges 30, the latter adapted to seat on the flanges 8 40 of the fire pot casing, and the adjacent flanges of each section being adapted to be bolted together, as indicated by the bolts 31. Similarly, the fire pot casing is provided with vertical end flanges 32, bolted together 45 by the bolts 33.

It will be seen from Figs. 2 and 3 that the jacket or sheathing for the cover is cut away to register with the openings 25 and 26 of the transverse passageway.

50 18 designates conventionally a low pressure oil burner of the type corresponding in detail to that illustrated in the W. W. Case United States Patent #1,003,873, of September 19, 1911, which burner is provided 55 with a nozzle 17 passing through the bore 16, and a fuel supply pipe 35, leading from a suitable reservoir, not illustrated. An air supply pipe 36 also leads to the burner and communicates with a fan blower 37 directly 60 connected to and driven by an electric motor 38, or connected thereto by a belt or chain connection, the fan blower 37 being adapted to deliver to the burner the air necessary to atomize the oil at a constant pressure of about six ounces. For convenience

of location, the fan blower and motor are preferably mounted within the space 2 formed between the base supports 1, the motor in the drawings being shown as supported on a pedestal 38^a. This use of a low pressure oil burner with a low pressure fan blower not only saves expense in construction and operation, but also avoids the objectionable roar of high pressure burners having positive blowers requiring several 75 horse power to operate them.

In the air pipe line 36, between the fan blower and the burner, there is provided an elbow or connection 39 in which are threaded laterally disposed pipes 40 lying substantially parallel and adjacent to the rear sheathing 5, which pipes are capped at their ends, as at 41, and are provided on their top surfaces with a longitudinal series of orifices 42, adapted to deliver jets of air upwardly to protect the operative, regulating the burner, from excessive heat from the opening 25. Also, at the top of the forge is arranged a pair of angle bars or brackets 43 to which is secured a vertically disposed plate or shield 44 by means of bolts 45, which also protects the eyes of an operative at the rear of the forge from any blast of flame or intense heat emerging from the opening 25.

95 It will be understood that the pyramidal projections or baffling means 14 may be of larger dimensions than shown and the side walls 14^b are preferably curved, forming concave surfaces the same as the upper and lower faces 14^a, the same being true with reference to the projections 15.

100 It is believed that the operation will be obvious from the foregoing description, but may be briefly referred to as follows: By 105 regulating the delivery of air and oil to the burner 18, the oil is minutely atomized and commingled with the air from the low pressure fan blower, so that complete combustion takes place within the combustion chamber, eliminating the disagreeable smoke and the forming of carbon in the forge, a highly objectionable feature in oil forges. The flame from the nozzle 17 is directed against the baffle or projection 14, 110 and, owing to the pyramidal shape of the baffle projection, the hot flames and gases are split up and caused to diverge downwardly, upwardly and laterally in a swirling fashion and the flames and hot gases, diverted to the opposite side of the combustion chamber, are similarly caused to swirl around by the deflecting surfaces of the pyramidal projection 15, and finally swirling upwardly are again deflected inwardly and downwardly by the curved surfaces 20 and the overhanging lip 21, so that the heat in the flame chamber of the forge is greatly intensified.

115 120 125 130 The drill steel is inserted in the forge

through the opening 26 above the flame chamber, and, while being heated, may be watched by the operative, as contradistinguished to the operation of embedding the 5 end of the drill steel into a burning mass of coal or coke.

Having thus described my invention, what I claim is:

1. In an oil forge, the combination of a 10 fire pot, having a bowl shaped bottom, curving upwardly and merging into oppositely disposed projections forming means for baffling and causing the flame and heated gases to swirl around within said fire pot, one of 15 said projections having a flame opening therethrough; and a fuel burner discharging through said flame opening into contact with the baffling projection opposite thereto, substantially as described.
2. In an oil forge, the combination of a 20 fire pot forming a flame chamber and having an internal wall curving upwardly and inwardly at its upper edge, providing an inwardly overhanging ledge extending 25 around the top of said flame chamber; a baffling projection formed on one side face of said chamber; and a fuel burner on the op-

posite side of said chamber and discharging against said baffling projection, substantially as described.

3. In an oil forge, the combination of a 30 fire pot forming a flame chamber and having a bowl shaped bottom portion, and an upwardly and inwardly curved upper portion forming an internal deflecting ledge extending around the top of said flame chamber; a pair of oppositely disposed baffling members projecting inwardly and forming substantially pyramidal continuations of the central portion of said chamber; a fuel burner 40 discharging, through a flame opening extending through one of said baffling members, against said opposed baffling member; and a top for said forge, an opening being provided between said top and said flame chamber, for inserting the work to be forged, 45 substantially as described.

In testimony whereof, I affix my signature, in presence of two witnesses.

WILLIS W. CASE, JR.
